(57) **CLAIM**

The ornamental design for a bottom rail for architectural covering, as shown and described.

DESCRIPTION

FIG. 1 is a reduced isometric view of the bottom rail of the present invention shown in the preferred environment of a retractable Venetian blind-type product.

FIG. 2 is a top isometric view of the bottom rail.

FIG. 3 is a front elevation of the rail shown in FIG. 2.

FIG. 4 is a top plan view of the rail.

FIG. 5 is a left end elevation of the rail.

FIG. 6 is a right end elevation of the rail.

FIG. 7 is a rear elevation of the rail; and,

FIG. 8 is a bottom plan view of the rail.

The broken lines are for illustrative purposes only and form no part of the claimed design.

FIGS. 2, 4, 7 and 8 have been shown broken away for ease of illustration.

It is certified that error appears in the above-identified patent and that said Letters Patent is hereby corrected as shown below:

The title page, showing illustrative figures, should be deleted and substitute therefore the attached title page.

Delete drawing sheets 1 through 3 and replace with formal drawing sheets 1 through 3 attached.

Signed and Sealed this

Twentieth Day of March, 2007

A handwritten signature in black ink, appearing to read "Jon W. Dudas". The signature is written in a cursive style with a large, stylized "J" at the beginning.
